UNITED STATES PATENT OFFICE.

JOHN H. WRIGHT, OF BRIDGEPORT, CONNECTICUT.

FRICITION-CLUTCH.

SPECIFICATION forming part of Letters Patent No. 288,291, dated November 13, 1883.

Application filed May 9, 1883. (No model.)

To all whom it may concern:

Be it known that I, JOHN H. WRIGHT, of Bridgeport, in the county of Fairfield and State of Connecticut, have invented certain new and useful Improvements in Friction-Clutches; and I do hereby declare the following to be a full, clear, and exact description of the invention, such as will enable others skilled in the art to which it appertains to make and use the same.

My invention relates to friction-clutches, the object being to avoid complication and expense in construction, and provide a clutch which shall be simple and durable in construction and adapted to be manufactured at small expense.

The invention consists in the combinations of parts hereinafter fully described, and pointed out in the claims.

In the drawings, Figure 1 represents a side elevation of a shaft-pulley and my improved friction-clutch devices. Fig. 2 is a similar view taken from the opposite side of the pulley. Fig. 3 is a vertical section on the line *xx* of Fig. 1, and Fig. 4 represents the split ring of the clutch detached.

A represents a shaft formed with a shoulder, *a*.

B represents a pulley mounted upon said shaft, and adapted to rest against the collar *a*, and provided at its opposite side with a hub, *b*, over which is secured a cap or clamping-thimble, *C*, the latter being bored out to fit upon the shaft *A*, and provided with perforations *cc*, adapted to receive a pin, *D*, which passes through the shaft and secures the cap in place. The pulley *B* is annularly recessed to receive a split ring, *D'*, which latter is provided with a perforated lug, *d*, adapted to receive a screw, *d'*, which passes through the pulley *B* to secure the ring in place. This ring *D'* is formed with arms *E E*, extending at a right angle to the ring and parallel with each other. These arms *E E*, project through an elongated slot *e*, formed adjacent to the periphery of the pulley, and the outer side of each arm is formed with a notch or recess, *e'*, adapted to receive the upperend of a pivoted lever or jaw, *F*. These levers or jaws *F F* are pivotally secured (one on each side of the shaft *A*) to the side of the pulley *B* opposite to that upon which the split ring rests. The

pivots or screws *ff* pass through the upper ends of the jaws. The lower ends of the latter are free to move outward; but their inward movement is limited by stop-pins *gg*, secured to the pulley.

H represents a loose sleeve mounted upon the shaft *A*, and formed with a laterally-projecting collar or hub, *h*. This collar or hub *h* is adapted to be forced between the jaws *F F*, thus forcing outward the lower ends of the latter, and securely holding the collar *h* by the spring action of the split ring, whose projecting arms, as above stated, engage the upper ends of the pivoted jaws. The pulley *B* is held securely upon the shaft, to revolve therewith, by the clamping cap or thimble *C*, and the slipping or sliding of the loose sleeve *H* effects the frictional connection or disconnection of the two pulleys.

My improvement, as thus described, is susceptible of slight alterations and modifications in form and construction; hence I do not limit myself to the precise construction herein shown and described, but reserve to myself the right to make all such changes as may properly fall within the scope of my invention.

Having fully described my invention, what I claim as new, and desire to secure by Letters Patent, is—

1. In a friction-clutch, the combination, with the shaft, the cap having a pin which secures it thereto, and the pulley secured to the cap, and thereby rigidly to the shaft, said pulley being formed with an elongated slot, of the split ring secured to one side of said pulley, and having notched arms projecting through said slot, the levers pivoted to the pulley, having their short arms fitted in notches formed in the split-ring arms and their longer arms crossing the center of the pulley, and the loosely-mounted sleeve having its periphery tapering at one end and adapted to be forced between said levers or jaws, substantially as set forth.

2. In a friction-clutch, the combination, with a shaft having an annular shoulder formed thereon, and a slotted pulley adapted to bear against said shoulder, of a clamping cap or thimble adapted to be rigidly secured to the shaft, a split ring secured around said cap, and having notched arms projecting through the slot of said pulley, the jaws pivotally secured

to the pulley, so that their upper ends will engage said arms to contract the split ring, stoppins for limiting the movement of said jaws, and a loosely-mounted sleeve having an annular portion adapted to enter and be held between said levers or jaws, substantially as set forth.

In testimony whereof I have signed this specification in the presence of two subscribing witnesses.

JOHN H. WRIGHT.
